FIG. 2

UNITED STATES PATENT OFFICE

2,041,137

PAPERMAKER'S FELT

John P. Koester, Piqua, Ohio

Application January 10, 1936, Serial No. 58,592

1 Claim. (Cl. 139—383)

The invention relates to woven textile fabrics (usually woolen) known to the paper and pulp industry as papermakers' felts. The principal object of my invention is to produce felt that will increase the drainage of water, lengthen the life of the felt, and reduce cost over present methods of constructing and maintaining papermakers' felt.

Another object is to provide felt having uniformly distributed stock or pulp supporting portions and uniformly distributed water drainage openings of relatively large size. In the process of making pulp or paper, these large openings permit the rapid drainage of water, allowing lessening of the normal pressure necessary on press rolls of the paper machine, and in turn increasing the life of the felt as it lightens the friction now necessary where felt passes through the press rolls. Moreover, the pulp or paper being delivered to the driers of the paper machine will have more water removed than is permitted by types of felts now being used, and increased production can be had because the sheets will be delivered to the driers in a drier condition than when using present types of felts, thus allowing the machine to be run at a greater speed. The cost of drying paper or pulp will in this manner be greatly reduced.

Papermakers' felts are usually made entirely of all wool yarns and it is customary to weave them considerably wider than the desired finished size, these felts being shrunk, felted or fulled by the application of soap, moisture and pressure, in machines known as fulling mills. Heretofore, in attempting to make felts of unusually open construction, it has been found impossible to finish such felts and obtain an evenly balanced fabric, due to the filling slipping on the warp, causing heavy and light spaces in the finished fabric, but a further object of my invention is to overcome these difficulties by making use of a special weave which is such that the warp and filling strands will not relatively slip on each other during finishing but will remain set.

45 I have shown the preferred embodiment of the invention in the accompanying drawing.

Fig. 1 is a fragmentary elevation.

Fig. 2 is a much exaggerated sectional view on line 2—2 of Fig. 1.

50 Fig. 3 is a diagram showing the weave.

The preferred construction will be specifically described with the understanding, however, that within the scope of the invention as claimed, variations may be made. Woolen yarn is preferably used but other yarns may be employed if

desired. It is preferable, however, that the yarn be of such fibrous nature that the peripheral fibres of the various reaches, hereinafter referred to as strands, may be thoroughly interlaced to screen the water drainage openings against passage of paper stock therethrough, without materially interfering with drainage of water through said openings. Each strand may consist of one piece of yarn, or a plurality of pieces disposed side by side and woven as a single strand in the weaving of the felt.

5 Warp strands are disposed in groups 5, there being three warp strands 6, 7 and 8 to each of these groups in the present disclosure. The strands 6, 7 and 8 of each group are uniformly spaced apart a relatively slight distance, for instance, slightly less than the diameter of the strands, and the groups 5 are spaced apart a relatively great distance, preferably a distance two or more times the diameter of the strands. 10

The filling strands are disposed in groups 9, there being three strands 10, 11 and 12 to each of these groups, in the present showing. These strands 10, 11 and 12 are spaced apart to correspond with the spacing of the warp strands 6, 7 and 8, and the groups 9 of filling strands are spaced apart to correspond to the spacing of the groups 5 of warp strands. 15

The warp and filling strands are interwoven to provide the felt with uniformly spaced stock-supporting portions and with large water drainage openings between said stock-supporting portions. These stock-supporting portions due to the spacing of the warp strands 6, 7 and 8 and the filling strands 10, 11 and 12, are of reticular form. For specific reference hereinafter, the alternate stock-supporting portions are denoted by the reference character 13 and the stock-supporting portions intervening between said portions 13, are denoted by the character 14. 20

In the present showing, the weave is such that the alternate stock-supporting portions 13 each comprise the two outside warp strands 6 and 8 of one warp strand group 5 both passing over the two outside filling strands 10 and 12 of one filling strand group 9, the central warp strand 7 of said one warp strand group passing under all three of the filling strands 10, 11 and 12 of said one filling strand group, and the central filling strand 11 of said one filling strand group 50 passing over all three of the warp strands 6, 7 and 8 of said one warp strand group. The weave of each of the intervening stock-supporting portions 14 is the reverse of the weave of the alternate portions 13. 45

By the particular weave shown and described, the reticular stock-supporting portions 13 and 14 possess small water drainage openings 15 and elongated water drainage slots 16, and large water drainage openings 17 exist between said stock-supporting portions. The peripheral fibers 18 of the strands are so interlaced that they screen the various openings and slots against passage of pulp or stock therethrough, without materially interfering with the drainage of water through said openings and slots, as I have illustrated in Fig. 2. These fibers may be carded and left with a rather loose fluffy pile at one side of the felt and may lie more compactly at the opposite side, or may be disposed in any other preferred way, according to the character of the paper or pulp to be handled.

By providing the novel felt structure shown and described, or an equivalent thereof, the felt possesses uniformly distributed stock or pulp-supporting portions and large uniformly distributed water drainage openings between said portions, and said portions and openings will maintain their uniform distribution during the finishing of the felt in a fulling machine or in any other desired way, instead of the strands becoming bunched or compacted in certain zones and widely spaced in others, as commonly occurs when finishing papermakers' felts of the types commonly employed. Thus, not only is the stock or pulp better supported to form better paper or the like but water permeability is materially increased. The felt, therefore, will enable the papermaker to increase the speed of his driers and thereby increase the production, resulting in lower operating costs. Less pressure on the pressing rolls is required to remove an equal amount of water from the sheet of pulp or paper, which will materially increase the life of the felt, thus resulting in lower operating costs. Should equal pressure be applied to the pressing rolls, the improved felt will enable the rolls to press more water from the sheet, thus causing the same to be delivered to the driers with less water content, which means that less steam will be required to remove the remaining moisture, decreasing cost for steam generation. Considerable expense

will be saved by mills using the invention, due to lowering yearly costs for felts, decreasing the amount of steam for the driers, permitting machines to be operated at higher speeds with increased production, etc.

While I have illustrated the preferred construction in the drawing and have herein specifically described the same, it is to be understood that variations may be made within the scope of the invention as claimed.

I claim:

Papermaker's felt comprising groups of fibrous warp strands, there being three of these warp strands in each group uniformly spaced apart relatively short distances, said groups being uniformly spaced apart relatively great distances; and groups of fibrous filling strands, there being three of these filling strands in each group spaced to correspond with the spacing of the warp strands of any group, the groups of filling strands being spaced to correspond with the spacing of the groups of warp strands; said warp strands and filling strands being interwoven to provide the felt with reticular woven uniformly distributed stock-supporting portions and with large uniformly distributed water drainage openings between said stock-supporting portions; the weave being such that the alternate stock-supporting portions each comprise the two outside warp strands of one warp strand group both passing over the two outside filling strands of one filling strand group, the central warp strand of said one warp strand group passing under all three of the filling strands of said one filling strand group, and the central filling strand of said one filling strand group passing over all three of the warp strands of said one warp strand group; the weave of the stock-supporting portions intervening between said alternate portions being the reverse of the weave of said alternate portions; the peripheral fibers of the strands being so interlaced as to screen the water drainage openings against passage of stock therethrough without materially obstructing the drainage of water through said openings.

JOHN P. KOESTER.
